UNITED STATES PATENT OFFICE.

EPAMINONDAS A. STATHOPOULO, OF NEW YORK, N. Y.

BANJO.

Application filed January 24, 1925. Serial No. 4,360.

This invention relates to musical instruments and pertains more particularly to stringed instruments of the banjo type.

It is an object of this invention to provide 5 an instrument which will produce an improved tone quality. It is a further object of the invention to provide an instrument which shall be strong and durable and yet simple in construction.

10 Other objects and advantages will appear hereinafter.

A preferred embodiment of the invention selected for purposes of illustration is shown in the accompanying drawings, in which,

15 Figure 1 is a top plan view of a banjo, part of the head being broken away to better illustrate the construction of certain parts.

Figure 2 is a section on the line 2—2 of Figure 1.

20 Referring to the drawings, the main frame 1 of the instrument comprises an annular rim which is preferably built up as shown in the drawings of a series of strips or laminations 2 glued or otherwise fastened together in the usual manner. Resting on the upper edge of the main frame 1 is an annular metal ring 3 which may be referred to as the tone chamber casting. This casting which forms one wall of the tone chamber 4 is provided with a series of radial openings 5 which permit free 25 passage to and from the tone chamber of the sound waves created when the instrument is played. Between the openings 5 are provided a series of shoulders 6 on which the annular ring 7 is adapted to rest.

Surrounding the upper portion of the main frame 1 and preferably replacing the upper portion of the outer lamination 2 thereof is a metal band 8 which projects upwardly above 30 the upper edge of the main frame as illustrated to form the outer wall of the tone chamber 4. Radial projections 9 formed in the casting 3 project outwardly to contact with the metal band 8 for a purpose herein- 35 after described. Immediately below the lower edge of the metal band 8 and contacting therewith for a purpose hereinafter explained is a bracket band 10 of metal surrounding the main frame and preferably inset, as shown, 40 into the body of the main frame as by cutting away a portion of the outer laminations.

The head 11 is mounted over the annular ring 7 and the upper edge of the metal band 8 and the edges thereof are fastened in the usual

manner to the flesh hoop 12 above which is 55 mounted the usual straining hoop 13. The usual hooks 14 are provided to stretch the head, these hooks passing through suitable openings in the bracket band 10.

A tone reflector is provided at the back of 60 the instrument comprising a shallow concave back 15 and a rim 16. The upper side of the rim 16 is grooved to form a shoulder 17 into which the outer edge of the bracket band 10 is adapted to seat. The tone reflector may be 65 conveniently attached to the instrument by means of bolts 18 which pass upwardly through the openings 19 formed in the bracket band and having on their outer ends thumb screws 20.

70 When the instrument is played as by causing vibration of the strings 21, corresponding vibrations are set up in the head 11 which, transmitted to the outer air, provide the characteristic banjo tone. It has been found a 75 difficult problem to provide a banjo which will produce a sweet and mellow tone without the undesirable "tinny" quality frequently observed and still provide sufficient body or tone volume so that the instrument 80 can be heard when played in conjunction with other instruments as in an orchestra.

In the present embodiment the provision of the metal band 8 contacting directly with the head and also contacting directly at its other 85 end with the bracket band 10, which, in turn supports the tone reflector, has been found to solve this problem satisfactorily for the instrument produces a tone possessing body, or that penetrative quality which causes it to 90 heard when played with other instruments; yet the undesirable "tinny" quality is lacking.

The tone reflector 15, as its name implies, reflects the sound waves produced by the 95 head outwardly through the openings 19 in the bracket band. These sound waves may either be produced by the main portion of the head 11 or by that portion covering tone chamber 4.

100 The vibrations so produced are transmitted through the ring 7 to the casting 3 and thence through radial projections 9 to the metal band 8 and thence through the bracket band 10 to the tone reflector which serves to amplify and 105 transmit them to the outer air. In addition vibrations pass directly from the portion of the head covering the tone chamber 4 to the

metal band 8 and thence as before to the tone reflector. It will be observed that in each case a direct metallic connection is provided through which vibrations may be transmitted from the head to the tone reflector. These vibrations so transmitted are modified by the wooden rim which also transmits some of the vibrations to such extent that the "tinny" quality ordinarily associated with all metal banjos is lacking, but at the same time the tone produced has adequate body.

The sum total of the sound waves and vibrations thus produced creates the composite wave which is transmitted to the ear.

15 It is to be understood that the invention may be variously modified and embodied within the scope of the subjoined claims.

I claim as my invention:

1. In a banjo having the usual head and 20 strings, in combination, a wooden main frame, a tone reflector, and means including a metal band of substantial thickness surrounding the main frame providing a direct metallic connection between the head and 25 tone reflector for the transmission of sound vibrations.

2. In a banjo having the usual head and 30 strings, in combination, a wooden main frame, a tone reflector, and means including a metal band of substantial thickness surrounding the main frame, and a metal bracket band also surrounding said frame, said bands having abutting surfaces, providing a continuous metallic connection between the 35 head and tone reflector for the transmission of sound vibrations.

3. In a banjo having the usual head and 40 strings, in combination, a wooden main frame, a metal band surrounding the main

frame, an annular metallic ring seated on 40 said main frame, said ring being provided with radial projections contacting with said metal band, a metal bracket band also surrounding said main frame, a tone reflector, and means to secure said tone reflector to said 45 bracket band, said metal band, annular metallic ring and metallic bracket band providing a continuous metallic connection between the head and tone reflector.

4. In a banjo having the usual head, straining hooks and strings, in combination, a main frame, a straining hook carried thereby, a metallic bracket band surrounding said frame, said hoop being engaged by one end of 50 said straining hooks and said band providing an anchoring means for the other end of said straining hooks.

5. In a banjo having the usual head, straining hooks and strings, in combination, a main frame, a metallic bracket band surrounding said frame, said band providing an anchoring means for said straining hooks, a tone reflector, and means for securing said tone reflector to said bracket band, said bracket band being provided with sound 60 openings.

6. In a banjo having the usual head, straining hooks and strings, in combination, a main frame having a groove therein, a metallic bracket band surrounding said frame and 70 positioned in said groove, said band providing an anchoring means for said straining hooks.

In testimony whereof, I have signed my name to this specification this 22nd day of 75 January, 1925.

EPAMINONDAS A. STATHOPOULO.
